PERIODIC SWITCH

Milo F. Miller, Kansas City, Mo.

Application January 10, 1944, Serial No. 517,626

1 Claim. (Cl. 175—335)

1

This invention relates to electrical sound producing instruments and has for a primary object, the provision of a switch capable of successively energizing a number of electro-responsive instruments whereby each is brought into play as a portion of the periodic switch is moved through a path of travel.

One of the important objects of this invention is the provision of a periodic switch for multi-tone chimes or the like, which switch embodies means movable upon the shifting of a weight, which weight is mounted to respond to the influence of solenoids that are energized by the manual closing of a switch.

A yet further object of this invention is to provide a periodic switch of the aforementioned general character, wherein is provided a number of contact points, all in circuit with current responsive devices and each successively engageable by a companion contact point movable from one to another by parts responsive to the shifting of weight due to the energization of the coils of appropriately disposed solenoids.

This invention has for a still further object to provide a periodic switch capable of successively energizing a number of current responsive devices and including means for controlling the speed with which the current responsive devices are actuated and with means for automatically returning the parts of the periodic switch to normal position after all of the series of contact points have been engaged.

More specifically the instant invention has for its aim the provision of a periodic switch wherein a rocker arm is employed to support a shiftable weight upon the movement whereof, in one direction, the rocker arm travels to carry a single contact brush over a series of contact points, after which the said weight is shifted back to the point of beginning and the rocker arm together with the associated brush, is automatically returned to a normal condition.

Further objects of the invention, including a number of ways of producing periodic switches, will appear during the course of the following specification, referring to the accompanying drawing wherein:

Fig. 1 is a schematic view illustrating the electro-mechanical features of a periodic switch made in accordance with this invention.

Fig. 2 is a fragmentary cross sectional view taken on line II—II of Fig. 1; and

Fig. 3 is a diagrammatical, electro-mechanical view illustrating a chime system having a periodic switch made in accordance with a modi-

fied form of the invention associated therewith.

A practical manner of applying the periodic switch is illustrated in Figs. 1 and 3 of the accompanying drawing. The need for successively causing a group of chimes to be sounded at suitable intervals and through inexpensive means embodying this invention, comprises that part of the equipment illustrated in Fig. 1, for example, with the several chime bars 10, 12, 14 and 16 mounted on conventional tubes 18, 20, 22 and 24. The cores 26, 28, 30 and 32 are reciprocably mounted within double coils 34, 36, 38 and 40 respectively, and when one coil of each unit is energized, the core will be withdrawn to a normal position.

The source of energy is illustrated as a battery 42, but it is understood that the current may be obtained through any suitable source of electricity capable of energizing the several cores 15 of the units.

A rocker arm 44, channel shaped in cross section, as shown in Fig. 2, slidably carries a coil 46 which is joined to a similar coil 48 by rod 50. Coil 46 surrounds a core 52 rigid with the end of rocker arm 44, and core 54 rigid with the other end of rocker arm 44 is surrounded by coil 48. Arm 44 is pivoted adjacent its center by a pin or the like 56, journaled in bearings 58. Pin 56 is rigidly mounted through the employment of 20 a bracket 60.

A series of contact points 62, 64, 66 and 68 are in circuit with the portions of coils 34, 36, 38 and 40 arranged to draw cores 26, 28, 30 and 32 toward their respective chime bars 10, 12, 14 and 16. Contact point 70 is joined through herein-after identified conductors, to the portion of coils 34, 36, 38 and 40 adapted to draw cores 26, 28, 30 and 32 from the said chime bars or to a normal position.

Another contact point 72 is joined by wire 74 to coil 46 on rocker arm 44. Contact point 76 is connected to contact point 70 by wire 78 and a contact point 80 is connected to manually operate switch 82 by wire 84.

All of the contact points just enumerated, 62, 64, 66, 68, 70, 72, 76 and 80, are in alignment to be successively swept by brush 86 mounted on piston 88 that moves along the cavity formed within housing 90, of insulating material. A long contact 92 against which brush 86 is pressed, is likewise carried in housing 90 and the relation of brushes 86 and 92, is as illustrated in Fig. 1. The contact bar 92 is connected to battery 42 by conductor 96. Switch 82 is joined to coil 48 by 45 wire 96, and coil 46 is joined to contact point 72

by wire 74. Coils 48 and 46 are joined to battery 42 by conductors 100, 102, 104, 106, 108, 110 and 112.

Piston 88 is joined to one end of rocker arm 44 by link 114 pivoted as at 116 and to compensate for the arcuate path of travel of the end of arm 44 above housing 90, said housing is hingedly mounted as at 118 to any suitable support 120.

The speed with which rocker arm 44 travels about the pivotal point 56 is determined by a dampening device 122 filled with liquid 124 and having a piston 126 secured by link 128 to the end of rocker arm 44 opposite to that with which is joined link 114.

A series of ports 130 formed through tubular stem 132 of piston 126, permits the passage of liquid 124 from one side of piston 126 to the other side thereof. These ports 130 are arranged in an inclined path so that a plug 134 may be shifted to open a predetermined number of the ports to control the speed of travel of rocker arm 44. Cylinder 122 is hingedly mounted as at 136 to a support 138.

The operation of the switch and its associated electro-responsive sound producing elements is as follows:

Assuming the position of the parts to be as illustrated in Fig. 1, the two points of switch 82 are closed and coil 48 is energized to shift its weight and the weight of coil 46 to the left along rocker arm 44. Current is supplied to coil 48 when switch 82 is closed through wires 98 and 84, contact point 80, brush 86, brush 94, contact bar 92, wire 96, battery 42, wires 112, 110, 108, 106, 104, 100 to coil 48. Such energization of coil 48 will cause the same to shift longitudinally onto core 54 and move rocker arm 44 to force brushes 86 and 94 into housing 90. The escape of liquid from one side of piston 126 to the other side thereof, through ports 130, will determine the speed of travel.

As piston 88 is lowered, brush 86 will first engage contact point 76 to energize that portion of coil 40 that withdraws core 32 from its related chime bar 16. The circuit causing such movement is as follows:

Contact point 76, wire 140, contact point 70, wires 142 and 144 to the lefthand portion of coil 40, thence through wires 146, 148 and 112 to battery 42. From battery 42 the circuit is completed through wire 96, contact bar 92, brushes 94 and 86 to contact point 76.

When contact point 62 is reached by brush 86, core 26 is drawn to the position shown in Fig. 1 by energizing the righthand portion of coil 34 through the following circuit:

Contact point 62, wire 150 to the coil 34, wires 152, 154, 106, 108, 110 and 112 to battery 42—wire 96, contact bar 92, brushes 94 and 86 to contact point 62. Thus, as contact point 62 is passed, chime bar 10 will be sounded.

When contact point 64 is reached, chime bar 12 will be sounded because core 28 will be drawn thereagainst through the energization of the righthand portion of coil 36 through the following circuit:

Wire 156, coil 36, wires 158, 160, 108, 110, 112, battery 42, wire 96, contact bar 92, brushes 94 and 86 to contact point 64. The next succeeding chime bar 14 is sounded by moving core 30 thereagainst when the righthand portion of coil 38 is energized through the following circuit:

Contact point 66, wire 162, coil 38, wires 164, 166, 110, 112, battery 42, wire 96, contact bar 92, brushes 94 and 86 to contact point 66. The last

chime bar 16 is sounded when the righthand portion of coil 40 is energized to draw coil 32 against the bar. The following circuit is closed when brush 86 reaches contact point 68:

Wire 168 to coil 40, wires 170, 172, 112, battery 42, wire 96, contact bar 92, brushes 94 and 86.

The continued downward movement of piston 88 brings brush 86 into contact with point 72, whereupon coil 46 on rocker arm 44 is energized to shift the weight to the right and return the arm to the position shown in Fig. 1. The energization of coil 46 is through the following circuit:

Wire 74, coils 46, wires 102, 104, 106, 108, 110, 112 to battery 42, wire 96, contact bar 92, brushes 94 and 86 to contact point 72.

On its way back to the position shown in Fig. 1, from the lowermost point reached in its path of travel, piston 88 draws brush 86 across contact points 70, 68, 66, 64, 62, 76 and 80 in the order mentioned. When brush 86 reaches contact point 70 on its upward stroke, the lefthand portions of coils 34, 36, 38, and 40 are energized to withdraw cores 26, 28, 30 and 32 from their places against bars 10, 12, 14 and 16. The circuit which is closed to withdraw core 26, is as follows:

Contact point 70, wires 142, 174, 176, 178 to coil 34, wires 160, 154, 106, 108, 110, 112, battery 42, wire 96, contact bar 92, brushes 94 and 86 to contact point 70. To withdraw core 28, the circuit is closed as follows:

Wires 142, 174, 176, 182, coil 36, wires 164, 160, 108, 110, 112, battery 42, wire 96, contact bar 92, brushes 94 and 86 to contact point 70. Similarly, core 30 is withdrawn through closing of the following circuit:

Wires 142, 174, 186, 188, 166, 110, 112, battery 42, wire 96, contact bar 92, brushes 94 and 86 to contact point 70. Thus, all of the cores 26, 28 and 30 are set for movement toward their respective bars and when brush 86 reaches contact point 76, bar 32 is re-set as above set down. Obviously, when brush 86 travels across contact points 62, 64, 66 and 68, the chimes will be sounded by a successive striking of bars 10, 12, 14 and 16, all as clearly indicated herein.

In the form of the invention illustrated in Fig. 3, the principle of operation remains substantially the same, as clarified above, and while the mechanical and electrical embodiments are slightly different, the basic idea of sounding a number of chime bars 200, 202, 204 and 206 at intervals remains the same. These several bars are each associated with resonating tubes 203, all of identical character. A solenoid is associated with each of the aforesaid bars and cores 210, 212, 214 and 216 are reciprocably mounted within their respective coils 218, 220, 222 and 224. A spring 225 on each core respectively yieldably maintains the core in a normal position shown in Fig. 3.

Rocker arm 226 is pivotally mounted intermediate its ends as at 230 and carries a double coil solenoid at one end, the core 232 whereof is free to shift as coils 234 and 236, as the case may be, are individually energized.

A weight 238 secured to core 232 moves therewith and shifts the balance of arm 226 to cause a movement of piston 240 in cylinder 242. Cylinder 242 is formed of insulating material and hingedly mounted as at 244. The space within cylinder 242 not occupied by piston 240, has a filling of electrical conducting liquid 246. A passage 248 formed as shown and controlled by needle valve 250, has an open side to permit liq-

uid 246 to engage contact points 252, 254, 256, 258 and 260. These points are located in alignment and as piston 240 moves down, liquid 246 is forced upwardly through passage 248 and into engagement with the contact points just enumerated.

A brush 262 carried by piston 240 is engageable with contact point 264 when the equipment is in a normal position. Liquid 246 is always in engagement with contact point 266 which is joined to battery 268 by wire 270. A one-way ball valve 272 permits the flow of liquid 246 from passage 248 when piston 240 moves to the position illustrated.

A manually operable switch 274 is connected to contact point 264 by wire 276. The other side of this switch 274 is joined to coil 236 by wire 278. Contact point 252 is connected to coil 234 by wire 280 and coil 234 is joined to battery 268 by wires 282 and 284. Coil 236 is likewise connected to battery 268 through the medium of wires 282 and 286. One end of each of coils 218, 220, 222 and 224 is joined to battery 268 by wires 288, 290, 292 and 294 respectively, all of which have one end joined to a common terminal wire 290 extending from one pole of the battery.

Contact point 254 is connected to coil 218 by wire 298. Contact point 256 is joined to coil 220 by wire 300. Contact point 258 is joined to coil 222 by wire 302, and contact point 260 is joined to coil 224 by wire 304.

The operation of the form of the invention illustrated in Fig. 3 is not basically different from the manner in which the form of the invention illustrated in Fig. 1 functions. When switch 274 is manually closed, coil 236 on arm 238 will be energized to shift weight 238 to the left, whereupon piston 240 will be forced down to raise liquid 246 into passage 248. As the level of the liquid rises, contact point 260 is first reached. The circuit for energizing coil 236 when switch 274 is closed is as follows:

Wire 278, coil 236, wires 286, 282 and 296, battery 268, wire 270, contact point 266, liquid 246, piston of conducting material 240, brush 262, contact point 264 and wire 276 back to switch 274. Downward movement of piston 240 is started and chime bars 206, 204, 202 and 200 are sounded in the order mentioned.

The interval between tones is governed by the needle valve 250 and if the periods are to be changed adjustment of this needle valve is easily accomplished through the employment of the parts illustrated.

Coil 224 is energized when liquid 246 reaches contact point 260 through the following circuit:

Contact point 260, wire 304, coil 224, wires 294, 296 to battery 268, wire 270, contact point 266, liquid 246 to contact point 260. Core 216 will be quickly jerked against bar 206 and its associated spring 226 will withdraw the core to its normal position. The strength of these springs 226 is such as to overcome any tendency of the coils to maintain the cores against their respective bars

and only the initial surge will draw the cores to a sounding position.

A liquid 246 reaches contact points 258, 256, 254, coils 22, 220, 218 will be energized as just set down with respect to coil 224. The circuits for these coils need not be traced.

When liquid 246 reaches contact point 252, coil 234 on arm 228 is energized to draw weight 238 back to the position shown in the drawings. The 10 circuit closing this coil is as follows:

Point 252, wire 280, coil 234, wires 284, 282 and 296 to battery 268, wire 270, contact point 266, liquid 246 to contact point 252. As piston 240 is lifted, liquid 246 will flow back into the bottom of cylinder 242 through valve 272, whereupon the instrument is in a normal position to have the cycle of operation repeated when switch 274 is again closed.

Obviously, electrical and mechanical apparatus of a character different from that illustrated and described, might be employed to embody the invention without departing from the spirit of the invention or scope of the appended claim.

Having thus described the invention, what is claimed as new and desired to be secured by Letters Patent is:

In a periodic switch of the character described, a series of contact points in circuit with current-responsive devices; a movable element for bringing an electrical conductor in said circuit into successive circuit-closing relation with the series of contact points; a rocker arm connected to said element; and means for rocking said arm in one direction from a normal position to impart movement to said element, said means for rocking the arm being a shiftable weight movable longitudinally along the arm in one direction by a first solenoid and movable in the opposite direction longitudinally along the arm by a second solenoid, one of the solenoids being in circuit with one of the contact points of said series thereof, the other solenoid being in a circuit having a manually operable switch the closing whereof energizes the solenoid to initiate movement of the rocker arm movable element having hydraulic means for varying the rocking speed of the arm with respect to its two directions of travel.
